A. R. SMITH.

PROTRACTOR FOR LAYING OFF LINES, ANGLES, AND ELEVATIONS IN BUILDING AND SIMILAR WORK.

APPLICATION FILED JAN. 20, 1921.

1,401,200.

Patented Dec. 27, 1921.

FIG. 2.

FIG. 10.

FIG. 5.

Arthur R. Smith,
Inventor
By Watson, Felt, Morse & Grindle,
Attys.

UNITED STATES PATENT OFFICE.

ARTHUR R. SMITH, OF NEW ALBANY, INDIANA.

PROTRACTOR FOR LAYING OFF LINES, ANGLES, AND ELEVATIONS IN BUILDING AND SIMILAR WORK.

1,401,200.

Specification of Letters Patent. Patented Dec. 27, 1921.

Application filed January 20, 1921. Serial No. 438,768.

To all whom it may concern:

Be it known that I, ARTHUR R. SMITH, a citizen of the United States, and resident of New Albany, in the county of Floyd, State of Indiana, have invented certain new and useful Improvements in Protractors for Laying off Lines, Angles, and Elevations in Building and Similar Work, of which the following is a specification.

10 This invention resides in a simple, light, easily portable device for use by builders and contractors and others engaged in analogous work and who are not skilled engineers or provided with expensive scientific instruments in practically and efficiently laying off or determining the desired lines, angles and approximate elevations necessary in their work. It is designed to save at least part of the time required and trouble encountered heretofore in doing such work and to enable the work to be done more accurately as well as more rapidly. The novel features of the device will be understood from the following description and claims 25 taken with the drawings. In the drawings:

Figure 1 is a perspective view of a device embodying my invention suspended on a line ready for use, the line being partly broken away for clearness;

30 Fig. 2 is a top plan view of the lower longitudinal arm or member of the device shown separately;

Fig. 3 is a cross section through the two arms and their pivot connection, the arms 35 being in this instance one above the other and parallel;

Fig. 4 is a side view of a modified construction where the two arms shown parallel in full lines are made in sections and provided with hinges near their centers for folding into the position shown in dotted lines;

Fig. 5 is a similar view of another modification in which each arm is made of a tubular central portion in which the end portions telescopically slide;

Fig. 6 is a detached side view of a portion of the longitudinal arm or member at one end showing the hooked support engaging 50 the supporting line and the clamping screw to prevent end movement;

Fig. 7 is an end view of what is shown in Fig. 6;

Fig. 8 is a detached side view of a portion of the longitudinal arms at the opposite

end from that illustrated in Fig. 6 showing the hooked support engaging the line:

Fig. 9 is a side view of what is shown in Fig. 8, and

Fig. 10 is a top plan view of the cross arm 60 detached.

As will be seen by reference to Fig. 1 the particular embodiment of the invention there shown includes an upper cross arm *a* made in the form of an elongated flat strip 65 of wood or other suitable material and a lower slightly longer longitudinal arm or member *b* also made in the form of an elongated flat strip of suitable material such as wood. These two arms are pivoted together 70 so as to permit relative rotary turning to bring them into any desired angular relation and the lower arm has concentric with the pivot semicircular side extensions and the upper arm has a side notch or cutaway portion with a concentric circular inner surface. The pivot is preferably not midway of the length of the arms but in each case is somewhat nearer one end than the other as shown. To secure proper balance however 80 the pivot is in the longitudinal center line of each and the material of the arms on opposite sides is so proportioned that the center of the pivot connection is approximately the center of gravity of each arm. 85 This may be accomplished by cutting away the sides of the arms the necessary amounts toward their ends as shown leaving the central parts full width.

The cross arm *a* has secured to its under 90 surface around the pivot a vernier which is in the form of a metal plate such as brass making contact on its lower surface with the top of the lower arm *b* as shown in Fig. 2 and having a circular margin forming the 95 visible bottom in the notch or cutaway portion of the upper arm *a* and projecting circularly therefrom. The lower longitudinal arm or member *b* has secured to its upper surface concentric with the pivot and lying partly on the semicircular side extensions a circular plate having a circular inner margin surrounding the outer margin of the vernier and is in the form of a protractor with the necessary markings. It 100 will of course be understood that the markings on the vernier and protractor are such as to indicate the angular relations of the arms *a* and *b*. The pivot connection between the members consists of an interiorly 110

screw threaded thimble *m* extending upwardly in a hole in the lower arm *b* and provided with a lateral flange at its lower end bearing on the lower surface of arm *b* 5 and an exteriorly threaded thumb screw *e* extending downwardly through a hole in arm *a* and engaging the threads of thimble *m* and having an upper enlarged head extending laterally over and engaging the upper 10 per surface of the upper arm *a*. It will be noted that this thumb connection permits easy clamping of the two members together in any adjusted position but when released permits free turning. The thumb 15 nut *e* preferably has a central hole or bore longitudinally thereof all the way through both arms whereby a pin or ten penny nail *l* may pass down through it with its point projecting below the device as shown in 20 Fig. 3 and that pin or nail may be driven into the top of a wooden stake or other fixed object to support the device.

The upper cross arm *a* has on its surface near its ends small and short similar upwardly projecting pins *f* arranged in a central position laterally and in line with the center of the pivot connection. These are to enable the operator when the device is adjusted to the right position in use to locate accurately the angle indicated by stretching a line along the arm *a* in the line of the two sights or pins. The lower arm *b* is provided near its ends with centrally arranged upwardly projecting hooks *g* as 35 a means for engaging a stretched wire, cord or similar element to support the apparatus. In the form shown these supports consist of small metal rods screwed into the upper face of arm *b* and having their upper ends 40 bent over into a transverse V shaped hook the inner points of the V being in each case on the center line of the arm *b* and in line with the center of the pivot connection between the arms. It will thus be observed 45 that the inclined surfaces of the hooks will cause them to slide automatically by the action of gravity on the wire or cord until it is at the apex and in the exact center supporting the arm *b* parallel to and with its 50 center line in the same vertical plane as said wire or line. This hook arrangement permits easy and accurate application of the device to the wire but to prevent longitudinal movement a screw threaded clamping pin *K* passes upwardly through the arm *b* at one end near one hook *g* and engages the under surface of wire or cord *h* and forces up into greater frictional contact with the hook. It will be observed by 55 comparing Figs. 2 and 10 that the upper arm *a* is enough shorter than arm *b* to permit it to turn to a position above and parallel to arm *b* without striking the hooks *g*.

In the modified form shown in Fig. 4 each 60 arm is formed of two end sections hinged

together near the middle but at some distance from the pivot and it will be noted that the transverse pivot line of the hinge for the upper arm *a* is along its upper margin permitting one end section to be turned 70 upward on over to a horizontal position on and substantially parallel to the other section as illustrated in dotted lines and that the transverse pivot line for the hinge connection of the lower sections constituting 75 arm *b* is along its lower margin permitting down turning of one section on the other and folding them as above indicated and as shown in dotted lines. Since this folding may take place when the arms *a* and *b* 80 are parallel one above the other the result is a very compact article of convenient shape and size for easy transportation. The thickness of the parts and the arrangement of the hinges are such that the projecting 85 thumb screw *e* and pins *f* do not interfere with the flat compact folding.

In the modification shown in Fig. 5 the central portions of arms *a* and *b* are tubular in form and are pivoted together as above 90 described as to the first form but it will be understood that the tubes are preferably formed of metal. They may be rectangular and flattened in cross section as shown or of any cross sectional shape desired. In addition to the central pivoted tubular sections rectangular in cross section both arms include end sections so shaped as to telescopically slide in the tubular ends to shorten up the device for packing and shipping.

It will be understood that the two modifications shown in Figs. 4 and 5 include hooks *g*, clamps *K*, sights *f* similar to those of the first described form and similar means for clamping the arms in position and determining the angle.

In Figs. 1 and 10 there is shown a level *o* mounted in or along the top of the upper arm or member *a* by which the operator can determine certainly whether that arm is in 110 an exact horizontal position. A longitudinally movable weight *p* may also be mounted in or on this arm to shift the center of gravity to bring it into proper horizontal position when the normal balance of the parts does not do this. The presence of this level furthermore permits the user to determine roughly the inclination of the ground when mounted on the wire or cord or even when supported in any other way.

The mechanical structure and operation of the device will be understood from the above description and therefore it is only necessary to describe the nature and manner of its use in practical work and the advantageous 115 functions and results secured by it. In laying off a building it is always easy to determine at least one building line and in using my invention a line or wire is stretched taut along that line in horizontal position and be- 120 125 130

yond its ends secured to stakes or other fixed supports. The apparatus is then mounted on said line by means of hooks *g* and is moved longitudinally thereon until the center of the pivot connection is directly over the exact corner point or end of the known line. The thumb screw *K* is then tightened to prevent any longitudinal movement of the device on the taut line. The upper arm *a* in a horizontal position is then turned on its pivot until the vernier and protractor indicate the known angle of the side line leading off from the line of the taut wire or cord. The thumb screw *e* of the pivot joint is then tightened to clamp the arms together at that angle to prevent turning. The side line is then easily run and determined by means of a cord or wire stretched on a line directly over the pins or sights *f* on the arm *a* and the distance to the next corner is measured on that line. By following this procedure for each side corner and line all of them can be quickly and accurately laid out. While the apparatus is especially adapted for use in building as above described it is also adapted for many other uses where it is desired to determine an angle or fix a line on a known angle. Its uses are not limited to those cases where it hangs from a stretched line even in determining the horizontal position or angle of lines and it may be used in positions different from horizontal to determine the pitch of roofs, the angle of the corners of buildings or even the incline of the ground. It may be used in taking levels where great accuracy is not necessary by merely sighting along the projecting pins *f*. In the preferred form the arms *a* and *b* are made of seasoned hard wood which when folded together make an article about 1" wide, $\frac{5}{8}$ " thick and five feet long and the vernier has about $\frac{3}{8}$ " exposure. In this preferred form a ten penny nail driven down through the central opening of thumb screw *e* into a stake or other fixed object will so fit and hold the device in fixed position without the line support and the arm *a* may be turned to the desired angle and a wire or line connected to the upper projecting end *b* of the nail and stretched off at the proper angle to fix the desired line. While I have described specific embodiments of my invention it will be understood that in its broader aspects it is not limited to the details of construction. Level *o* and weight *p* may be countersunk in arm *a*.

Having described my invention what I claim as new and desire to secure by Letters Patent is:

- 60 1. In a device of the class described the combination with an elongated member, of means thereon for supporting it from and below a stretched wire or cord in a definite fixed position on a vertical plane therewith, 125 65 a transverse member pivoted to said elongated member to turn horizontally thereon the portions extending on opposite sides being such as to balance each other, and circularly arranged scales carried by said members and concentric with the first point to indicate the angular relations of the members.

2. In a device of the class described the combination with an elongated member, of means thereof for supporting it from and below a stretched wire or cord in a definite fixed position on a vertical plane therewith, a transverse member pivoted to said elongated member to turn horizontally thereon, the portions extending on opposite sides being such as to balance each other, and circularly arranged scales carried by said members and concentric with the first point to indicate the angular relations of the members and means for clamping said transverse member in adjusted position.

3. In a device of the class described the combination with an elongated member, of means thereon for supporting it from and below a stretched wire or cord in a definite fixed position on a vertical plane therewith, a transverse member pivoted to said elongated member to turn horizontally thereon, the portions extending on opposite sides being substantially balanced normally, a level on said transverse member, longitudinally movable means on said transverse member for so regulating the balance as to make said transverse member rest in a horizontal position, and scales carried by said members concentric with the pivot point to indicate the angular relations of the members.

4. In a device of the class described, the combination with an elongated member, of means thereon for supporting it from and below a stretched wire or cord comprising upwardly extending hook members near its ends having contact surfaces inclined upwardly to sharp V-shaped points at the center, an adjustable clamp coöperating with one of said hooked members to so engage the wire or cord as to prevent longitudinal movement, a cross member having upwardly projecting sights thereon near its ends and pivoted to said elongated member in the line of said sights and in the line of the sharp points of said hooks for rotary movement thereon in a horizontal plane and coöperating means on said elongated and cross members concentric with the pivot point to indicate the angular relations of the members.

5. In a device of the class described, the combination with an elongated member, of means thereon for supporting it from and below a stretched wire or cord comprising upwardly extending hook members near its ends having contact surfaces inclined upwardly to sharp V-shaped points at the center, an adjustable clamp coöperating with one of said hooked members to so engage the

wire or cord as to prevent longitudinal movement, a cross member having upwardly projecting sights thereon near its ends and pivoted to said elongated member in the line of 5 said sights and in the line of the sharp points of said hooks for rotary movement thereon in a horizontal plane and coöperating means on said longitudinal and cross members concentric with the pivot point to indicate the 10 angular relation of the members and movable means for balancing said cross member in a horizontal position.

6. In a device of the class described the combination with an elongated member of 15 a cross member each having upwardly projecting pointed alining means near their ends, a pivot connection between the ends of said members in line with said alining points permitting relative rotating movement on 20 each other and permitting them to lie parallel close against each other when not in use, means at the pivot point for clamping said members together in adjusted position and coöperating means carried by said members concentric with the pivot point to indicate the angular relation of the members.

7. In a device of the class described the combination with an elongated member of a cross member each having upwardly projecting pointed alining means near their ends, a pivot connection between the ends of 30 said members in line with said alining points permitting relative rotating movement on each other and permitting them to lie parallel close against each other when not in use, means at the pivot point for clamping said members together in adjusted position and coöperating means carried by said members concentric with the pivot point to indicate the angular relation of the members, each member being formed of two end sections 35 transversely hinged together near the center whereby the sections may be folded together when not in use the hinge on each member facing oppositely from that of the other member so as to fold on opposite sides.

8. In a device of the class described the combination with an elongated arm or member having near its ends supporting means of a cross arm or member on said elongated member having near its ends upwardly projecting pins or sights, pivot connection between said members through approximately their centers of gravity embodying a thumb screw extending through alined openings in said members engaging at its inner end a flanged thimble in said elongated member and having at its outer end a head or thumb piece resting on said cross member and adapted to clamp the members together, a vernier of circular outline carried by said cross arm closely adjacent to and concentric with the pivot point and resting on said elongated arm and a protractor mounted on said elongated arm with its inner circular margin around and closely adjacent to the outer margin of said vernier.

9. In a device of the class described the combination with an elongated member of a cross member each having upwardly projecting pointed alining means near their ends, a pivot connection between the ends of 50 said members in line with said alining points permitting relative rotary movement on each other and permitting them to lie parallel close against each other when not in use, means at the pivot point for clamping said members together in adjusted position and coöperating means carried by said members concentric with the pivot point to indicate the angular relation of the members, each member being formed of two end sections 55 transversely hinged together near the center whereby the sections may be folded together when not in use the hinge on each member facing oppositely from that of the other member so as to fold on opposite sides.

10. In a device of the class described the combination with an elongated arm or member having near its ends supporting means of a cross arm or member on said elongated member having near its ends upwardly projecting pins or sights, pivot connection between said members through approximately their centers of gravity embodying a thumb screw extending through alined openings in said members engaging at its inner end a flanged thimble in said elongated member and having at its outer end a head or thumb piece resting on said cross member and adapted to clamp the members together, a vernier of circular outline carried by said cross arm closely adjacent to and concentric with the pivot point and resting on said elongated arm and a protractor mounted on said elongated arm with its inner circular margin around and closely adjacent to the outer margin of said vernier.

11. A device for determining a line at an angle to a stretched wire or cord comprising two thin elongated members pivoted together between their ends, means near the ends of one member for supporting the device from said wire with the pivot in the vertical plane of said wire, sights or projections near the ends of the other member in line with said pivot, adjustable means for automatically causing said last mentioned member to lie in a horizontal plane when supported by said first mentioned member, and coöperating means on said members concentric with the pivot point to indicate the angular relation of the member.

12. In testimony whereof I affix my signature.

ARTHUR R. SMITH.
